UNITED STATES PATENT OFFICE.

EMIEL R. FUCHS, OF NEW YORK, N. Y.

DOOR-SECURER.

No. 840,486.

Specification of Letters Patent.

Patented Jan. 8, 1907.

Application filed March 20, 1906. Serial No. 307,014.

To all whom it may concern:

Be it known that I, EMIEL R. FUCHS, a citizen of the United States, and a resident of the borough of Manhattan, city, county, and State of New York, (whose post-office address is No. 1088 Park avenue, New York city, New York,) have invented certain new and useful Improvements in Door-Securers, of which the following is a specification.

The present invention relates to means for securing a door against forcible entry, the object being to provide means which may be easily and quickly applied.

The invention comprises a bar which is adapted to be rigidly held between abutments on the door and floor, all as more particularly hereinafter described and claimed.

The invention will be understood by reference to the accompanying drawings, in which—

Figure 1 is an elevation of a portion of a door, showing my invention applied thereto; Fig. 2, a sectional elevation on the plane of the line 2 2 of Fig. 1. Fig. 3 is an enlarged front view of the means for moving the securing-bar, the latter being broken away and the covering-plate removed. Fig. 4 is a horizontal section on the plane of the line 4 4 of Fig. 3. Fig. 5 is a side view of the casing, partly broken away and with the lock removed. Fig. 6 is a view similar to Fig. 3 with the upper part broken away, showing the bar in its securing position. Fig. 7 is a horizontal section on the plane of the line 7 7 of Fig. 5. Fig. 8 is a detail view of a modification, and Fig. 9 is a detail view showing a modified form of securing-bar.

Similar reference-numerals indicate similar parts in the several views.

Referring to the drawings, the numeral 1 designates a portion of a door, 2 the door-jamb, and 3 the floor of a room or passage-way entrance into which is effected through the door. For the purpose of securing the door against forcible entry I provide a bar 4 of sufficient length for the purpose and which in practice may be made of one-half-inch iron. The lower end of said bar is stepped into a socket 5, seated in an opening in the floor 45 and constituting an abutment of sufficient strength to resist the thrust of bar 4. The upper end of bar 4 is retained in a casing 6, secured to the inner side of the door, said casing having an upwardly-extended curved portion 7, constituting a guideway for the bar when the door is opened or closed. When

the door is closed, the upper end of the bar lies between the bolt 8 of any ordinary type of lock 9, adapted to be operated by a key, and a block 10. The latter is supported between a guide-rail 11 and the upper wall of casing 6 and is held in normal position (shown in Fig. 3) by the action of a spring 12, bearing against a pivoted dog 13, which latter engages a stud 14 on the block. A pin 15, projecting from the upper wall of casing 6, serves to guide block 10 in its movements. The lower end of the casing is closed by a plate 16, on which is cast a lug 17 to prevent the spring 12 and dog 13 becoming displaced.

The guideway 7 is open throughout its length, and when the door is released from the bar 4 the latter occupies a position in a channel in the casing forming a continuation of the guideway, as indicated in Fig. 3. When the door is to be locked, the bolt 8 is thrown by a key and in its outward movement bears upon the bar 4, moving it against the stress of spring 12 to the position indicated in Fig. 6. In that position the upper end of bar 4 abuts firmly against the upper wall of casing 6 and is immovably held between said wall and socket 5, thus effectually resisting any effort to open the door from the opposite side. When the bolt 8 is retracted, the bar 4 will be returned to the position indicated in Fig. 3 by spring 12 acting through dog 13 and slide-block 10. The door may then be opened, and as it swings inwardly the bar 4 will move upwardly into the curved guideway 7, the lower end of said bar remaining in position in socket 5. The extent of the opening movement of the door depends upon the length of bar 4 and the angle at which it is set relative to the door. In practice an angle of about forty-five degrees permits the door to be opened sufficiently for ordinary purposes. The guideway 7 is laid out upon a curve sufficient to permit the movement of the bar 4 therein without wedging. When the bar is in the position shown in Fig. 3, it may be easily removed and put out of the way until required. When the bar 4 is in the position indicated in Fig. 3 or when the said bar is removed, the door may be temporarily kept closed by an ordinary form of latch-lock under the control of the handle 18.

In its broadest aspect the casing 6 constitutes an abutment for the upper end of bar 4 and socket 5 an abutment for the lower end of said bar, the latter when in position

to prevent the opening of the door being rigidly held between said abutments. The invention affords a means which may be easily and quickly applied to prevent the forcible entry of a door. It may be applied to any type of swinging door and is of particular advantage in connection with doors having glass panels, inasmuch as the breaking of the glass does not permit of the removal of the bar. During the daytime, when there is constant ingress and egress through the door, the bar 4 may be easily removed, as above indicated, by the occupant of the room, to be replaced whenever the room is to be vacated or at night, when it is desired to secure the door.

In Fig. 8 I have shown a slightly-modified form, in which the dog 13 is removed, the spring 12 in that case acting directly upon slide-block 10. In the preceding figures the bar 4 is shown straight throughout its length. In Fig. 9 I have shown a modified form of bar having an angular portion 4' adapted to rest in the channel in the casing.

25 What I claim, and desire to secure by Letters Patent, is—

1. The combination of a door, a securing-bar therefor adapted to rest against the door at an angle thereto, an abutment on the floor against which the lower end of said bar is set, a fixed abutment secured to said door,

and a key-actuated means for moving said bar laterally to bring its upper end under said latter abutment.

2. The combination of a door having a 35 casing secured thereto, a door-securing bar, a socket secured to the floor into which the lower end of said bar is stepped, said casing having a guideway, a wall against which the upper end of said bar is adapted to abut, and 40 means to move said bar laterally to bring its upper end into the guideway or under said abutting wall when the door is to be unlocked and locked respectively.

3. The combination of a door having a 45 casing secured thereto, a door-securing bar the upper end of which is retained by said casing, an abutment on the floor against which the lower end of said bar is set, an abutment fixed to the door, a lock having a 50 bolt adapted to engage said bar to move it into position under said door-abutment, and a spring in said casing to move the bar in a reverse position to release the door therefrom.

55 In testimony whereof I have hereunto signed my name in the presence of two subscribing witnesses.

EMIEL R. FUCHS.
